UNITED STATES PATENT OFFICE

AARON Z. SAVAGE, OF CANOE STATION, ALABAMA.

BORING-MACHINE.

SPECIFICATION forming part of Letters Patent No. 657,835, dated September 11, 1900.

Application filed January 31, 1900. Serial No. 3,540. (No model.)

To all whom it may concern:

Be it known that I, AARON Z. SAVAGE, a citizen of the United States, residing at Canoe Station, in the county of Escambia and State 5 of Alabama, have invented new and useful Improvements in Boring-Machines, of which the following is a specification.

This invention relates to boring-machines, and is especially designed for boring stumps 10 in order that the latter may be readily burned in preparing farm-lands; and it has for its object to provide a boring-machine of the character referred to which shall be strong and durable and at the same time light and 15 portable and which shall be simple in construction and effective in operation.

To these ends my invention consists in the features and in the construction, combination, and arrangement of parts hereinafter 20 described, and particularly pointed out in the claims following the description, reference being had to the accompanying drawings, forming a part of this specification, wherein—

Figure 1 is a side elevation of my improved 25 boring-machine, and Fig. 2 is a front elevation of the same.

Referring to the drawings, the numeral 1 indicates a spindle provided at one end with a thimble 2, adapted to receive the shank of 30 the auger 3, which is held in place in the thimble by a set-screw 4. The spindle is arranged to rotate in a cross-coupling 5, the laterally-projecting ends 6 of which are fitted in elbows 7. Rotatably arranged on the projecting members 6 of the cross-coupling are 35 two sleeves 8, to which are attached the upper ends of two rods 9, which constitute legs and operate to support the boring-machine. The rods or legs 9 are connected together by 40 a brace-rod 10. Screwed into the pipe-elbows 7 are two tubular sections 11, and screwed over said tubular sections are T-couplings 12, which form bearings, in which is journaled 45 a tubular shaft 13. On the shaft 13 is fixed a beveled gear-wheel 14, which gears with a similar gear-wheel 15, fixed on the upper end 50 of the spindle 1. Fixed on the opposite ends of the tubular shaft 13 are cranks, each comprising two pipe-elbows 16 and 17, united by a section of pipe 18, the elbows 16 being screwed over the ends of the shaft 13, and fit-

ted in the elbows 17 are rotatable knobs or handles 19 of ordinary construction.

The entire machine, excepting the gearing and legs, is formed from piping or tubing, 55 thereby combining great strength with lightness and permitting the machine to be manufactured at small cost.

In operating the machine the latter is supported in an approximately-upright position 60 on the legs 9, but leaning toward the stump being bored. By turning the cranks the tubular shaft 13 is rotated and through the gears 14 and 15 rotates the spindle 1 and the auger 3 carried thereby. By rotatably arranging the sleeves 8 on the ends 6 of the cross-coupling the machine may be moved backward and forward at will and the auger set at any desired inclination. In boring holes 70 in stumps the auger is set to bore the holes at a downward inclination to form draft-channels in which fire is placed to burn out and destroy the stump in a well-known manner.

While my improved machine is particularly designed for boring stumps, it may also 75 be employed for other purposes and especially where it is desired to bore holes at an incline, and by arranging the auger-spindle in a swiveled bearing, as shown, the machine may be reversed—that is to say, the auger may be 80 turned vertically upward so as to bore overhead.

Having described my invention, what I 85 claim is—

1. In a boring-machine, the combination with the tubular frame, of the cross-coupling carried thereby, the spindle journaled in the cross-coupling, a crank-shaft journaled in the frame at a right angle to the spindle, gearing for transmitting motion from the crank-shaft 90 to the spindle, an auger fitted in the spindle, and a support swiveled upon the laterally-projecting arms of the cross-coupling, substantially as described.

2. In a boring-machine, the combination 95 with the cross-coupling, of sleeves swiveled on the laterally-projecting ends of said coupling, legs attached to said sleeves, a spindle journaled in the cross-coupling, an auger fitted in the spindle, bearings supported by the 100 cross-coupling, a tubular crank-shaft journaled in said bearings, and gearing for trans-

mitting motion from the crank-shaft to said spindle, substantially as described.

3. In a boring-machine, the combination with the tubular frame comprising the cross-coupling, the elbows fitted on the laterally-projecting ends of the cross-coupling and the T-couplings carried by said elbows, of the tubular crank-shaft journaled in said T-couplings, the spindle journaled in said cross-coupling, gearing for transmitting movement from the crank-shaft to the spindle, an auger fitted in the spindle, and a support for the tubular frame, substantially as described.

4. In a boring-machine, the combination with the tubular frame comprising the cross-coupling, the elbows fitted on the laterally-projecting ends of the cross-coupling, and the

T-couplings carried by said elbows, of the crank-shaft journaled in said T-couplings and comprising the central tubing, elbows 20 fixed on the ends thereof, tubular sections fitted in said elbows, elbows fitted on the ends of said sections, handles fitted in the elbows, a spindle journaled in the cross-coupling, gearing for transmitting motion from the crank-shaft to the spindle, and an auger fitted in the spindle, substantially as described.

In testimony whereof I have hereunto set my hand in presence of two subscribing witnesses.

AARON Z. SAVAGE.
